ABSTRACT OF THE DISCLOSURE

The printing sectors of an adding or calculating machine are provided with outwardly yieldable type carrying sections. An aligning member is movable outwardly into engagement with detenting notches in the sections, the member flexing the sections to form a solid base against which type hammers impact.

This invention relates to data printing mechanisms such as those found in adding and calculating machines.

Many such machines embody pivoted sectors arranged in side-by-side relation. Type characters are spaced along the peripheries of such sectors against which a paper tape is imprinted, the particular characters being imprinted depending upon the setting of the sectors under control of a settable stop pin carriage or settable keys. In order to properly align the selected type characters to be printed along a printing line, an alignment element or bar may be moved into engagement with spaced detenting formations or notches on the sectors after the latter has been set and prior to the imprinting action.

Heretofore, problems have been encountered in causing the alignment element to accurately align all of the printing sectors due to minute variations in dimensions of the sectors and associated parts or due to necessary tolerances in such dimensions. For example, the alignment bar may firmly seat in the detenting notches of certain of the sectors to accurately align the same but not properly seat in others, thereby resulting in misalignment of the latter.

Also, if the alignment member is located diametrically opposite the printing line, any misalignment error between the member and the sector becomes twice as great at the printing line.

Although adjustment features may be provided and adjustments made or parts manufactured to greater accuracy in order to eliminate the above noted variations in dimensions, such features are relatively costly and the adjustments are time consuming.

Further, it has been found that when the sectors are loosely supported or the supporting means for the sectors is yieldable, the sectors may move slightly during the printing impact, resulting in a slight but noticeable double printing or smudging of the printed type characters.

The present invention overcomes the above problems by causing the alignment element to be moved substantially radially outwardly from the axis of the printing sectors into seating engagement with detenting formations formed on arcuate type character sections which are yieldably supported by the sectors proper. The alignment element is located directly in line with the printing hammers and is movable towards such hammers to seat in the detenting notches, causing the type character sections to yield outwardly slightly. Thus, the alignment element not only accurately aligns all of the sectors but also forms a solid base or anvil located closely adjacent the point of impact and against which the type character sections rest during the imprinting action to insure a clear, crisp imprint.

The invention also results in a more compact printer

2

mechanism since the alignment element is located within the configuration of the printing sectors.

Further, the printing sectors must differentially advance to different type printing positions prior to movement of the alignment element into type aligning position, and because of such difference in timing, separate actuating cams and cam operated mechanism have generally been provided heretofore.

The present invention enables a single cam and cam operated mechanism to both yieldably drive the sectors to different type printing positions and to thereafter actuate the alignment element, thereby simplifying the construction of the printing mechanism and reducing the cost of manufacture and assembly. Such construction also insures proper timing of the sector driving feature and the sector aligning feature.

It therefore becomes the principal object of the present invention to provide a highly reliable printing mechanism of the above type capable of accurate alignment of type characters and yet which has a minimum number of parts, is compact and simple and economical to manufacture and assemble.

The manner in which the above and other objects of the invention are accomplished will be readily understood in reference to the following specification when read in conjunction with the accompanying drawings, wherein:

FIG. 1 is a sectional elevation view, with parts broken away, of a ten key adding machine embodying a preferred form of the present invention.

FIG. 2 is a sectional view taken substantially along the line 2—2 of FIG. 1.

FIG. 3 is a sectional elevation view illustrating the drive mechanism for the type sectors and alignment bar.

FIG. 4 is a fragmentary enlarged view illustrating part of a type sector and its relation to the alignment bar.

FIG. 5 is a side view of a printing sector per se.

Describing the illustrated embodiment of the invention in detail the machine in which the invention is embodied is the well known and commercially available Addmaster adding machine which is disclosed basically in U.S. Pat. No. 3,113,719 issued to R. E. Busch on Dec. 10, 1963 and U.S. Pat. No. 3,132,582 issued to H. L. Clary et al. May 12, 1964. Reference may be had to these patents for a disclosure of operating instrumentalities not shown herein.

Amounts are entered into the machine through ten amount keys ranging in value from zero to nine, two of which keys are indicated at 11. Different functions of the machine, such as addition and subtraction operations, are controlled by depressing certain function control keys (not shown), each effective to cause a cycle of operation of the machine, during which time a main shaft 12 and a printer control shaft 13 are each rotated clockwise through one complete revolution.

An arcuate pin carriage generally indicated at 14 and carrying a field of coordinate arranged settable stop pins 15 is suitably guided for movement transversely of the machine under control of suitable escapement means operable by each amount key upon depression thereof.

Each of the amount keys 11 is guided for vertical movement and is connected to a respective flexible cable 16 which is guided for endwise movement in a curved guide channel formed in a stationary guide block 17. All of the cables are located in a vertical plane which lies coincident with a lefthand column of the stop pins 15 when the pin carriage is in its home position.

A plurality of plastic printing sectors 18 are independently and pivotally mounted in side-by-side relation on a support shaft 20 which is journaled in bearings 21 carried by side plates 22 and 23 forming part of the machine frame work.

Each sector 18 has a somewhat flexible arcuate type

section 24 which is integral therewith and supported thereby through end sections 26 and 27 of greater flexibility than the main section 24. The sections 24 extend over arcuate openings 28 in the sectors. Type characters 25 ranging in value from 0 to 9 are spaced along the length of each type section 24.

The printing mechanism includes a plurality of elongated type hammers 31 which are aligned with respective ones of the types of the printing sectors and are guided for endwise movement in a direction extending radially of the sectors by guide member 35 and 36.

Guide means including a guide channel 29 and guide member 39 guide a paper tape 33 over a printing ribbon 34 and under the hammers 31.

Leaf springs 32 are effective to impel the hammers endwise to impact the paper and thus transfer an imprint from aligned ones of the type characters 25 onto the tape during a midpoint in each machine cycle. Normally, however, the hammers are held in their illustrated positions by a cam 37 carried by the printer control shaft 13 and engaged by a cam follower 38 underlying the springs 32. During the printing phase of a cycle, the cam follower drops off a shoulder 40 of the cam 37 permitting the hammers to be impelled downwardly.

The sectors 18 are effective to transfer amounts to and from an accumulator generally indicated at 41 and, for this purpose, each sector has gear teeth 42 formed thereon and adapted to be meshed with gears 43 forming part of the accumulator.

Means are provided for yieldably advancing the various sectors 18 in a clockwise direction from their illustrated home positions during the first half of a machine cycle until shoulders 44 thereon arrest against set ones of stop pins 15 or until arrested by the accumulator during totaling and subtotaling operations. For this purpose, the sectors have arcuate openings 45 therein, through which extends a bail rod 46 carried by arms 47 and 48 which are fastened to the shaft 20. The rod 46 normally engages in shallow pockets 50 formed in flexible tails 51 integral with the sectors 18. The bail rod 46 also engages yieldable fingers 471 integral with the sectors and extending radially from shaft 20.

Also attached to the shaft 20 is a gear sector 52 which meshes with a gear sector 53 fulcrumed at 54 and carrying a cam follower roller 55 which rides in a cam race 56 formed in a cam 57 suitably attached to the drive shaft 12. The configuration of the cam race 56 is such as to impart a clockwise rocking movement of the bail rod 46 about shaft 20 during the first half of a machine cycle to thereby yieldably advance the various printing sectors 18 until they are differentially arrested by the stop pins 15 or by the accumulator 41 to position different ones of the type characters 25 under the printing hammers 31. During the latter half of a machine cycle the bail rod 46 engages the fingers 471 to return the sectors 18 counter clockwise to their illustrated home positions.

According to the present invention the type sections 24 have detenting notches 59 formed on the under edges thereof in radial alignment with respective ones of the type characters. The notches are engageable by an alignment bar 60 which extends across the various sectors and is slideable radially of the sectors and in line with the type hammers in guide slots 61 formed in the side plates 22 and 23.

Plastic sleeves 62 are secured to the alignment bar 60 to locate the bar endwise. The bar 60 is engageable by cam formations 63 extending from the arms 47 and 48. Such cam formations are normally angularly spaced from the alignment bar 60, as seen in FIG. 3, so that they will not engage the bar until the various printing sectors 18 have been either fully or partially advanced clockwise by the bail rod 46.

It will be noted that the detenting notches 59 are V-shaped and are adapted to mate with a similarly shaped formation along the upper edge of the alignment bar 60. 75

Normally, however, the bar 60 is located in a lower illustrated position within the arcuate openings 28 formed in the sectors by gravity so that the apex 65 of its upper edge just clears the tips of teeth 66 formed between adjacent ones of the notches 59.

When the machine is at rest, and the sectors are in their illustrated home positions, FIGS. 1 and 4, the bail rod 46 presses against the fingers 471 causing the latter to yield slightly to maintain shoulders 67 on the sectors in contact with the side of the alignment bar 60. In this condition, the apex 65 of the bar is out of direct alignment with the overlying partial portion of the rightmost notch 59 by a small angular distance "a" of approximately two degrees. Also, in this condition, the shoulders 44 of the various sectors are likewise out of alignment with the lowermost stop pins 15 by similar amounts so as to prevent any possible interference between any set ones of such stop pins and the shoulders 44 during initial setting and escapement of the pin carriage when entering amounts therein.

During a cycle of the machine, and after the sectors 18 have been advanced clockwise to their digitized positions, the alignment bar 60 is cammed outwardly, as described heretofore, causing the bar to firmly seat in the overlying notches 59, camming all sectors slightly in either direction, to thereby accurately align all of the various type characters with a printing line extending under the various hammers. Those sectors located at zero are moved approximately 2 degrees clockwise by the bail rod 46, depending on tolerance or errors of dimensions and are then centered by engagement of the bar 60 with the surface 59a. Other sectors are moved slightly in either direction depending on such tolerances.

In order to insure that the bar seats firmly in all of the notches to accurately align the selected type characters of all of the sectors with the printing line, the bar is overdriven slightly outwardly thereby causing all of the type sections 24 to yield outward slightly. Therefore, the bar will form a solid base against which the printing impact by the hammers 31 is made. This will result in a minimum amount of smudging and will present a clear imprint of the type characters of the paper tape 33.

During return movement of the bail rod in a counter clockwise direction after printing has occurred, the rod 46 will engage the fingers 471 and likewise return the sectors. At this time, the bar 60 is allowed to drop by gravity into its illustrated position. In the event it should stick or bind in the guide slots 61, the adjacent sloping surfaces of the notches 59 will cam the same downwardly, out of engagement with the notches.

I claim:

1. A data printer comprising, a plurality of sectors arranged side-by-side and independently pivotal on a common axis, arcuate sections extending concentrically of said axis and supported by said sectors, said arcuate sections being flexible radially outwardly of said axis, type characters spaced along the outer periphery of each of said arcuate sections, detenting formations spaced along the inner periphery of each of said arcuate sections and aligned radially with respective ones of said type characters, means for differentially advancing said sectors about said axis whereby to present certain of said type characters to a printing line, an aligning member extending through said sectors under said arcuate sections and extending parallel to said axis, said aligning member being mounted for movement radially of said sectors and in line with said hammers, means for moving said aligning member radially outwardly from said axis whereby to engage overlying ones of said detenting formations and to flex said sections outwardly,

means for guiding a record medium over said sectors, and type hammers moveable toward said arcuate sections to transfer an imprint from aligned ones of said type characters onto said record medium.

2. A data printer according to claim 1 comprising: means for impelling said type hammers towards said sections after said sections have been flexed outwardly.

3. A data printer according to claim 1 wherein said detenting formations comprise V-shaped notches and said aligning member comprises a complementary shape effective to seat in said notches.

4. A data printer according to claim 3 wherein said V-shaped notches are in alignment with respective ones of said type characters radially of said sectors.

5. A data according to claim 1 wherein said aligning member is moveable in a direction aligned with the direction of movement of said hammers.

6. A data printer according to claim 1 wherein said arcuate sections are integral with said sectors.

10

5

7. A data printer according to claim 1 wherein said advancing means comprises a drive cam and cam follower means including yieldable means operable by said cam; and cam means operable by said cam follower means after advancement of said sectors for camming said aligning member into engagement with said overlying ones of said detenting formations.
